UNITED STATES PATENT OFFICE.

WILLIAM T. CONNOR AND CLEMENS HESS, OF ROCHESTER, NEW YORK, ASSIGNEES TO JOSEPH D. STEEFEL, HERMAN D. STRAUSS, AND WILLIAM T. CONNOR, COMPRISING THE FIRM OF STEEFEL, STRAUSS AND CONNOR, OF ROCHESTER, NEW YORK.

COAT.

No. 889,761.

Specification of Letters Patent.

Patented June 2, 1908.

Application filed March 17, 1908. Serial No. 421,740.

To all whom it may concern:

Be it known that we, WILLIAM T. CONNOR and CLEMENS HESS, citizens of the United States, residing at Rochester, in the county 5 of Monroe and State of New York, have invented certain new and useful Improvements in Coats; and we do hereby declare the following to be a full, clear, and exact description of the invention, such as will enable 10 others skilled in the art to which it appertains to make and use the same.

Our invention relates to improvements in coats, and the object of our invention is to produce a coat which may be tightly buttoned around the neck, like an ordinary automobile coat, or worn loosely with the lapels down, as coats are usually worn, such coats being designed for the use of both sexes.

With these objects in view, our invention consists in the constructions and combinations of parts as hereinafter described and claimed.

In the accompanying drawings—Figure 1 is a perspective view showing the coat tightly buttoned around the throat for use as a storm coat, and Fig. 2 is a perspective view of the upper part of the coat, parts being bent back and parts being shown in dotted 30 lines.

a represents the body of the coat, and *b* the collar thereof, which collar is not made integral with the part of the coat which folds over to form the lapel, but is separated 35 therefrom by a considerable cut, as shown at *c*. On the outside of the inner part of the collar are two or more fastening means, *d*, like the half of a glove button, and an eye *e* is also provided to engage a hook *f* on the 40 other part of the collar. Inside the part which is folded over to form the lapel, at its upper portion, are two fastening means, *g*, like the other half of a glove button.

When the coat is to be worn as an ordinary 45 coat, and not as a storm coat, the fastening means *g* are caused to engage the fastening means *d*, and thereby the collar and lapel present substantially the appearance of an ordinary coat. When, however, it is desired 50 to use the coat as a storm coat, the upper one of the fastenings *g* is engaged with

the lower one of the fastenings *d* on each side, one lapel is folded in, and the other is folded across it and secured by buttons, as shown in Fig. 1. The hook *e* may then be engaged 55 with the eye *f*, if desired, but these parts are not strictly necessary.

By the construction shown, we have devised a neat appearing and well fitting coat, which can be used either as a storm coat or 60 as an ordinary coat, and which on casual inspection is not distinguishable from either.

We claim:

1. A coat, provided with a collar, said collar being fastened to said coat at the back 65 but separated therefrom at the front for a considerable distance, said coat collar being provided on the outside of its inner fold with a plurality of fastening devices, and the body 70 of said coat being provided on its inside just above the lapel with a plurality of fastening devices, any one of which is adapted to engage any one of the fastening devices on the coat collar, said coat being provided with buttons and button holes, whereby said coat 75 may be worn as a storm coat or as an ordinary coat, substantially as described.

2. A coat, provided with a collar, said collar being fastened to said coat at the back but separated therefrom at the front for a 80 considerable distance, said coat collar being provided on the outside of its inner fold with a plurality of fastening devices, and the body 85 of said coat being provided on its inside just above the lapel with a plurality of fastening devices, any one of which is adapted to engage any one of the fastening devices on the coat collar, said coat being provided with buttons and button holes, the ends of said collar being provided with fastening devices 90 adapted to be engaged with each other, whereby said coat may be worn as a storm coat or as an ordinary coat, substantially as described.

In testimony whereof, we affix our signatures, in presence of two witnesses.

WILLIAM T. CONNOR.
CLEMENS HESS.
